Patented May 18, 1915.

UNITED STATES PATENT OFFICE.

WILLIAM THOS. BAUGH, OF MADISON, GEORGIA.

WINDOW-CLEANER.

1,139,834.

Specification of Letters Patent. Patented May 18, 1915.

Application filed March 14, 1914. Serial No. 824,744.

To all whom it may concern:

Be it known that I, WILLIAM T. BAUGH, a citizen of the United States, residing at Madison, in the county of Morgan and State 5 of Georgia, have invented new and useful Improvements in Window-Cleaners, of which the following is a specification.

The invention relates to a window cleaner, constructed with a view to receiving and 10 carrying surplus water taken from the window in the wiping operation, whereby to prevent such water from running on to the wood work and soiling the same.

The main object of the present invention 15 is the provision of a window cleaner including a trough-shaped element arranged between the rubber and cleaner, the disposition of the element serving to receive and retain the water wiped from the window 20 during rubbing operation.

The invention in the preferred form of 25 details will be described in the following specification, reference being had particularly to the accompanying drawings, in

which:—

Figure 1 is a perspective view of the improved cleaner head. Fig. 2 is a transverse section of the same. Fig. 3 is a top plan view of the same.

The improved head for window cleaners 30 is constructed of three parts in so far as the metallic construction is concerned, which parts are preferably of galvanized sheet iron. The main section includes a plate 1 of appropriate length and width doubled upon itself to form a lip 2 of the double thickness of material and diverging from the upper edge of the lip to form flanges 3 and 4.

A trough member is arranged between the flanges 3 and 4, said trough member being 40 of triangular shape in cross section, and including side plates 5 and 6 and end plates 7.

A cleaning element such as strip of felt 45 or the like 8, is secured between one of the flanges as 3, and the wall of the side walls 6 of the trough, a rubbing element, as strip of rubber 9 is secured between the 50 other flanges 4 and the remaining side wall 5 of the trough, bolts 10 being preferably passed through the metallic portions to secure the parts in applied position.

The head includes a handle receiving socket constructed of a single strip bent to 55 form a circular casing 11, strip at the upper end being flattened as at 12 and flattened portion being passed through the opening 13 formed in the plate 1 in the fold forming the lip, rivets 14 being passed through the 60 lip sections and flattened portion to secure the socket in place.

In use, after the window has been cleaned in the usual manner so far as applying and rubbing the same is concerned, excess moisture is taken from the window by the use of the rubbing element. In this use, the cleaner is moved upwardly on the window pane, that is from the lower to the upper portion and the water and moisture taken from the 70 window pane by the rubber is delivered into the trough so that it is removed entirely from the pane in the removal of the cleaner.

What is claimed is:—

In a device of the class described, a holder 75 for cleaning elements comprising a member formed from a single piece of material bent upon itself at its longitudinal center to provide a lip, relatively yieldable diverging flanges formed on the upper longitudinal 80 edge of the lip, a second member of a length equal to the former mentioned member and having diverging side flanges arranged inwardly of and in spaced relation to the yieldable diverging flanges of the lip, end 85 plates combining with said second member to form therewith a trough, means passing through the flanges of the first member and the flanges of the 2nd member for causing the flanges of the 1st member to move in a 90 direction toward the diverging side flanges of the second member, said means also serving to connect and retain the second member to the first member, and a rubber strip secured between said members and adapted 95 to coöperate with the trough, whereby the excess moisture removed from a window pane by said strip will be delivered into said trough.

In testimony whereof I affix my signature in presence of two witnesses.

WILLIAM THOS. BAUGH.
